UNITED STATES PATENT OFFICE.

EDWARD BACKHOUSE, OF LONDON, ENGLAND.

PNEUMATIC-DISPATCH APPARATUS.

Application filed February 24, 1927, Serial No. 170,674, and in Great Britain February 1, 1926.

This invention relates to pneumatic dispatch apparatus of the kind consisting of a closed system of tubes along which carriers are conveyed pneumatically and discharged at the desired substations, and particularly such systems as are provided with means whereby, during the periods in which the transmissions are not being effected, the flow of air through the system is automatically reduced or stopped by devices controlled by timing mechanism, and the present invention has for its object to provide pneumatic dispatch apparatus of high efficiency and simple construction.

15 Heretofore attempts have been made to effect the same object by intricate mechanical or electrical mechanism, but such mechanism has been found to be liable to get out of order, and the present invention provides

20 means for effecting the same general object in a greatly simplified manner, with the avoidance of unnecessary levers and catches.

In one of these previously proposed devices, in order to automatically apply power when a carrier is inserted and to rapidly cut off the power when a carrier is ejected, the transmission tube is connected to vacuum by a balanced valve controlled by pressure changes in the line acting on a flexible diaphragm, there being also provided an auxiliary diaphragm or valve open at one side to atmosphere and at the other to the pipe line acting to disconnect the vacuum rapidly on the discharge of the last carrier. The first flexible diaphragm is open on one side to the pipe line and on the other to the atmosphere through a small permanent opening, and through a solenoid controlled valve the circuit of which is controlled by

35 the second diaphragm.

The present invention comprises pneumatic dispatch apparatus having automatic controlling apparatus, characterized by such apparatus having pneumatically operated controlling devices arranged in a valve controlled inlet to the system. The pneumatically controlled devices may be arranged in an inlet to the system separate from that through which the dispatch carriers are inserted.

The valve-controlled inlet is opened when the vacuum in the system is broken as by the insertion of a carrier through a dispatch orifice, and is closed again after a predetermined interval by timed mechanism.

In a conveying system to which this in-

vention is particularly applicable, each tube is in the form of a loop running from a central station to a sub-station and back again, so that transmissions can be made in both directions simultaneously. The several tubes are usually connected in parallel at the central station to the exhausting apparatus.

Various embodiments of the invention are illustrated by the accompanying drawings, wherein

Figure 1 is a partly sectional front elevation,

Figure 2 a side elevation, and

Figures 3 and 4 sectional and outside plan views of one modification of a valve inlet made in accordance with the present invention.

Figure 5 is a front elevation,

Figure 6 a side elevation and

Figure 7 a plan of a detail of the apparatus for applying the invention to a double tube system, while a further modification of a valved inlet is illustrated in sectional elevation in Figure 8, front elevation in Figure 9, Figure 10 being a sectional plan through B-B of Figure 9, and Figure 11 a sectional plan through A-A of Figure 8.

In the construction of the apparatus illustrated a carrier inlet 2 as arranged at a central position is provided with a spring-controlled or counterpoised door 3, the carrier being drawn through the tube in the usual manner by an induced current of air produced by an exhaust arranged at the opposite end of the loop. Adjacent the door covered inlet 2 of a dispatch tube 4 is fixed a controlling cylinder 5 provided at its lower end with a controlling valve 6 arranged to be opened by gravity and above which is a lateral opening 7 communicating by means of a port 9 with the dispatch tube 4 immediately above its door 3, so that after a carrier has been inserted in the dispatch tube 4 and its door 3 closed, air is drawn into the tube through passage 8 of the controlling valve 6 and the communicating passage 7 after the controlling valve 6 has been opened due to the vacuum in the system being destroyed by the opening of a dispatch door such as 3 for the purpose of inserting a carrier in the tube 4. The controlling valve 6 is raised to its seating automatically after a predetermined interval, and is held against its seating by atmospheric pressure as long as the tube 4 is un-

100
105
110

der vacuum. When a door such as 3 at a dispatch aperture is opened to insert a carrier either at a sub-station some distance along the tube or at the central station, the 5 vacuum is broken and the control valve 6 falls, thus permitting a flow of air through the system.

In the lower portion of the control cylinder 5 below the communicating passage 10 7 to the dispatch tube 4 is mounted a light disc 10 formed on the lower end of a sleeve valve 11 sliding on a tube 12 fixed axially in the control cylinder and provided with ports 13 which are covered by the sleeve 15 11 when the sleeve is raised. The said ports form a means of communication between the atmospheric or internal air pressure in the system and the upper side of an annular piston 14 sliding in the control cylinder 20 5 and on the central tube 12 therein. Suitable apertures 15 are provided in the upper portion of the central tube 12 so as to place it in communication with the cylinder 5 above the annular piston 14.

25 In a cover 16 of the control cylinder is provided a valve 17 adjustable from outside the cylinder and controlling a passage 18 between the upper portion of the cylinder 5 and a suction or vacuum pipe 19, which 30 pipe may be constructed as a supporting member of the apparatus. When the sleeve valve 11 at the lower portion of the control cylinder 5 is raised over the ports 13 in the central tube, the air is slowly extracted 35 from the cylinder 5 and the annular piston 14 is raised at a rate corresponding to the setting of the adjustable valve 17. The time for this operation is adjusted to suit the transit time of the carrier in the tube in 40 use. When the annular piston 14 nears the top of its stroke it engages with a cross member 20 extending through slots 21 in the central tube 12 and to which cross member 20 is fixed the upper end of a rod 21 45 passing through the central tube 12 and carrying at its lower end the valve 6 at the lower end of the control cylinder 5, and so cause the flow of air into the control cylinder 5 to cease and leave the sleeve valve 11 50 free to fall into the open position by gravity. The air pressure above and below the annular piston 14 is now equalized and the piston 14 falls to its lowest position in readiness for another transmission.

55 In apparatus of this kind it is desirable that the timing device should reset itself when further carriers are inserted in the tube before the first one has reached its destination. Obviously if the timing was 60 determined by the introduction of the first of a series of carriers, subsequently inserted ones would be trapped in the tube after the expiry of the original time interval. In the present invention a reset takes place each 65 time a dispatch aperture is opened for the

purpose of making a transmission, due to the fact that the flow of air is interrupted, and owing to the dropping of the sleeve valve air is allowed to flow through the central tube to the top of the annular piston, 70 which then falls to its original starting position.

Whilst it is essential that the resetting of the timing mechanism should take place on the insertion of each carrier in the tube, it 75 is not desirable that this should be brought about by the discharge of the carriers at the terminal points, such discharge causing a momentary interruption in the flow of air through the system. It has been ascertained that this discharge occupies a period of about half a second, whereas the insertion of a carrier cannot be accomplished in less than double this period. In the present invention therefore means are provided to 80 prevent the sleeve valve 11 from falling during the period occupied by the discharge of a carrier from the tube. The larger period however, occupied by the insertion of a carrier allows the valve to fall and the resetting to be accomplished. The delay of falling of the sleeve valve may be effected by any suitable apparatus such as by providing above the sleeve and fixed on the central tube an inverted dash pot 30 in which somewhat closely fits a disc 31 fixed on the upper end of the sleeve valve 11.

In the case of pneumatic tubes of considerable length or where longer time intervals are required and they cannot be conveniently obtained by the movement of the annular piston 14 alone, the time interval may be further extended by an auxiliary piston such as 40 Figure 8 working in an oil dash pot 41, or similar device, and this device may be attached to the lower end of the control cylinder valve rod 21.

The apparatus so far described is suitable for controlling lines of pneumatic tubing singly, but it is sometimes desired to link 110 up two or more tubes such as 50 and 51 Figure 5, provision being made to admit air to the tube it is desired to use. In such a system it is proposed to use the same timing device to control more than one tube. In 115 the case of a pair of tubes 50 and 51 this may be effected by connecting the open end of the control cylinder to the tubes by means of a two-way box 53 on the underside of which are arranged side by side the apertures for dispatching the carriers through either of the tubes each being closed by a hinged door 6^a, 6^b. Inside the box are provided ports 52 and 53 connecting the two tubes 50 and 51 with the air supply. A swing flap valve 54 is arranged for closing either one or other of these ports, and this valve 54 is operated by a vertical spindle 55 provided with a forked lever 56 which actuated by projections 57^a, 57^b on the hinged 120 125 130

tube closing doors 6^a and 6^b, so that when say the left hand door 6^a is open, the flap valve 54 would be thrown over to close the port 53 communicating with the right hand tube 51, and vice versa when the right hand door 6^b is opened. A spring-controlled plunger 58 operating a crank pin 59 is arranged to give the flap valve 54 a bias towards either side of a central line, so that it will remain on its seat when thrown over. Thus when the dispatch door for either tube is opened, the air admitting or control valve 6, see Figures 1 and 2, at the lower end of the control cylinder 5 is opened, and the air supply connected to the tube in use.

The modification illustrated by Figures 8 and 11 is for control apparatus requiring larger time intervals than for which the above apparatus is intended.

20 In this modification an oil dashpot 41 is attached to the lower end of the mechanism. The rate of movement of the main piston 14 is determined by the setting of a screw-down valve 60 in the piston 40 of the oil dashpot 41.

25 In this modification the inlet valve 17 shown in Figure 1 in the cylinder head 16 is not necessary, and as will be seen a simple connection is made to the suction pipe 62 above by a port 63 in the cylinder cap 64. The cylinder cap 64 is provided with a bracket portion 65 which is secured by a bearing member 66 and screws 67 to the pipe 62.

30 The method of operation is substantially the same as outlined in the previous modification and corresponding parts are given the same reference numerals. Assuming that no transmissions are being made in the pneumatic tube system, and the predetermined time intervals have elapsed, then the valve 6 will have been raised to this seat, and held there by atmospheric pressure—the whole system being under vacuum. Directly a dispatch aperture is opened at any point on the tube concerned, the valve 6 will fall off its seat on to a felt buffer 68.

35 The air will then be admitted to the tube through the passage 8 of the main valve 6, which will have the effect of raising the sleeve valve 11 and closing the ports 13, which constitute the means of communication between the underside and the upper-side of the main piston 14. As soon as this has been done, an upward force is exerted on the said piston, owing to the vacuum created above.

40 In the mechanism of the dash pot 41 a hook 70 on the lower end of the piston rod 21 however, is in engagement with a catch 71 on the oil dashpot piston 40 and the latter can only be raised at the rate permitted by the flow of oil through the adjustable valve 60 to the lower end of the piston 40.

45 After a predetermined interval of time, the

piston 40 will have been raised to a point where an extension 72 of the catch 71 engages with a fixed point represented by the step 74 on the downward projected pin 73.

The hook 70 is by this means released just 70 as a cross pin 75 reaches a sleeve 76 forming part of the main valve 6, and the latter is suddenly lifted to its seat.

In consequence of this, the sleeve valve 11 now falls to its lowest position, uncovering 75 the ports 13 and establishing a state of equilibrium in the conditions above and below the main piston 14. The latter is therefore deprived of its support, and together with the piston 40 in the oil dashpot 41, 80 will fall to the original position in readiness for a further transmission.

The resetting on the introduction of a subsequent carrier before the preceding one has reached its destination, is accomplished in 85 precisely the same manner to that previously described. It should be noted that as the piston 40 in the oil dashpot 41 falls by gravity, the oil is allowed to flow from the lower side to the upper side through the mushroom 90 valve 77.

95 Referring to piston 14 it will be noted that this is of the plain type and the portion 78 shown on the drawing represents a floating annular ring composed of compressed felt or other suitable material. A projecting pin 79 on the lower side of the piston 14 engages with a stationary fork 80 so as to prevent the hook 70 from turning out of position. The inverted air dashpot 30 shown 100 in Figure 1 as associated with the sleeve valve 11 has not been shown in Figure 8 but it is desired to retain the use of this feature when required with the modification shown in Figure 8.

105 What I claim and desire to secure by Letters Patent is:—

110 1. A pneumatic dispatch apparatus of the kind specified having pneumatically operated controlling devices arranged in a valve controlled inlet to the system, a gravity opened valve arranged to close the inlet of said valve controlled inlet to the system, a timing piston, an oil dash pot to which said piston is connected; said dash pot being arranged concentrically thereto, said piston having a spindle which passes freely through said gravity opened valve.

115 2. A pneumatic dispatch apparatus having automatic controlling apparatus in an air inlet to the system separate from the carrier inlet, a gravity opened valve, a disc movable freely in the air inlet passage by the suction of the system, timing mechanism for closing the valve having a piston operated by vacuum tank pressure, and means for placing the upper and lower sides of the piston in communication with one another, the gravity valve being arranged to close the separate air inlet completely and to be 120 125 130

opened and held open by gravity when both sides of the piston are placed in communication with one another, the disc operating the means for placing both sides of the piston in communication with one another.

3. A pneumatic dispatch apparatus having automatic controlling apparatus in an air inlet to the system separate from the carrier inlet, a gravity opened valve, a disc 10 movable freely in the air inlet passage by the suction of the system, timing mechanism for closing the valve having a piston operated by vacuum tank pressure, and means for placing the upper and lower sides of the 15 piston in communication with one another, the gravity valve being arranged to close the separate air inlet completely and to be opened and held open by gravity when both sides of the piston are placed in communication 20 with one another, the disc being operatively fixed to the means for controlling the passage placing the two sides of the piston in communication with one another.

4. A pneumatic dispatch apparatus having automatic controlling apparatus in an air inlet to the system separate from the carrier inlet, a gravity operated valve, and timing mechanism for closing the same operated by the suction of the system, means 25 for rendering the timing mechanism inoperative and dash pot mechanism for controlling the same, the gravity valve being arranged to close the separate air inlet completely, and open by gravity when the dash 30 pot has operated to render the timing mechanism inoperative.

5. A pneumatic dispatch apparatus having automatic controlling apparatus in an air inlet to the system separate from the carrier inlet, a gravity operated valve, and timing mechanism operated by a piston subjected to vacuum tank pressure through a 40

regulatable opening, means for connecting the piston with the valve, the valve being arranged concentrically with the piston and 45 to close the separate air inlet completely and to be held open by gravity and be closed by the suction piston.

6. A pneumatic dispatch apparatus having automatic controlling apparatus in an air inlet to the system separate from the carrier inlet, an air inlet valve closed by a cylinder and piston timing apparatus of which the rod is provided at its lower end with a hook, an oil dash pot having a piston provided with a pivoted catch, a catch releasing projection being provided in the oil dash pot, the pivoted catch being arranged to engage the hook on the rod of the timing piston and to be disengaged therefrom when a 50 projection of the catch engages the releasing projection.

7. A pneumatic dispatch apparatus having automatic controlling apparatus in an air inlet to the system separate from the carrier inlet, an air inlet valve closed by a cylinder and piston timing apparatus of which the rod is provided at its lower end with a hook, an oil dash pot having a piston provided with a pivoted catch, a catch releasing 55 projection being provided in the oil dash pot, and a rod depending from the timing piston, and a fork fixed in the cylinder of the timing apparatus, the hook being held in the path of the catch by the rod depending from the timing piston passing through the fixed forks so that the pivoted catch will engage the hook on the rod of the timing piston, and be disengaged therefrom when a 60 projection of the catch engages its releasing projection.

In witness whereof I affix my signature.

EDWARD BACKHOUSE.
